BRACKET MOUNTING FOR BULLDOZER
SUPPORT FRAME OR THE LIKE

Harry W. Fall, Morton, Ill., assignor to Caterpillar Tractor Co., Peoria, Ill., a corporation of California
 Filed Mar. 31, 1960, Ser. No. 18,947
 1 Claim. (Cl. 287—20.2)

This invention relates to the mounting or securing of load sustaining brackets on a hollow frame or other plate-like structure by welding wherein concentrated stresses are likely to cause fracture of the frame adjacent the bracket.

The invention is disclosed herein in its application to the C-frame of an angling type bulldozer wherein it has proven particularly effective but its usefulness in other environments will be come apparent from the description which follows.

It is an object of the invention to provide an improved method for securing a load sustaining bracket to a plate or member fabricated from plate-like parts and to provide a structure of greater strength than is attained by welding a bracket directly to the surface of such a member.

It is a further object of the invention to provide a bulldozer frame of superior strength by employing a method of securing brackets thereto which does not induce a concentration of stresses in the areas subject to heavy loading.

Further and more specific objects and advantages of the invention are made apparent in the following specification wherein the invention is described in detail by reference to the accompanying drawings.

In the drawings:

FIG. 1 is a schematic plan view of a tractor with an angling type bulldozer mounted thereon and showing the positions of the brackets with which the present invention is concerned;

FIG. 2 is a fragmentary side sectional view of the C-frame showing the bracket secured to the C-frame in accordance with the present invention; and

FIG. 3 is a view similar to FIG. 2, but illustrating a conventional bracket securing method, and indicated as the prior art.

The tractor shown at 10 in FIG. 1 of the drawings is provided with an angling type of bulldozer which comprises a C-frame 11 pivotally secured to the track roller frames of the tractor not shown by means of trunnions 12. The blade 13 is connected at a central point to the forward end of a C-frame, as by a pivot pin 14, and angle braces 15 extend between the outer ends of the blade rearwardly to brackets 16 welded to the top of the C-frame. The blade is illustrated in its straight position but may be angled to one side of the other by the use of auxiliary brackets shown as two rear back brackets 17 and two front brackets 18. The braces 15 are connected with the brackets by tapered pins 19 which are received in tapered openings in the brackets and are provided with spherically contoured outer ends for connection with the ends of the braces.

To dispose the blade at an angle, one of the braces is moved to a rear bracket 17 on one side of the C-frame and the other is moved to a front bracket 18 on the opposite side. In this position of the blade, the front bracket which is being used is subjected to heavier loads than the other brackets when they are in use and failures have been encountered in the area of the frame immediately adjacent the bracket and usually directly behind it.

C-frames are conventionally formed as a hollow beam fabricated from steel plate sections welded together and the failures which have been encountered have been ana-

2

lyzed as resulting from the concentration of stresses at a point where there is an abrupt change in section or thickness of the stressed material. This may readily be understood from FIG. 3 showing a conventional bracket 18 secured in place on the C-frame 11 as by a fillet weld 21. Due to the nature of the load applied to the C-frame when the bulldozer blade is in its angled position, the top portion of the frame in the area of the front bracket is placed in tension by a force which tends to bend the frame and consequently failures in the form of cracks such as indicated at 22 in FIG. 3 occur in the area where a stress riser has been caused by the abrupt change in thickness of material caused by welding the bracket 18 to the plate which forms a part of the C-frame. Such failures have been obviated by the present invention by a method and construction which serves to locate the weld in areas of low nominal stress or in an area of increased section and, therefore, greater strength.

The attachment of a bracket to a C-frame in accordance with the present invention is shown in FIG. 2 wherein a bracket is shown as comprising a forged plate 24 with a bracket extension 25 welded thereto. The plate 24 has a circumscribing flange or marginal thickness which is the same as the plate of which the C-frame is fabricated and is secured, within an opening which has been cut in the C-frame for its reception, by a full penetration V-butt weld as shown at 26 so that this weld is placed in an area of constant section rather than in an abrupt change in section such as the weld 21 of FIG. 3. It is possible in accordance with the present invention to make the entire bracket shown in FIG. 2 as a single forging but since forgings of this general shape are complicated and costly to make, the portion 24 is formed with an integral base for the portion 25 of greater thickness than its marginal edge and joined thereto by a large radius fillet as shown at 27. The member 25 is then secured in place as by a weld 28 at an area which because of its greater thickness has greater strength and is less subject to failure. Thus by positioning the weld in areas of low stress and great strength, the present invention has overcome failures which were experienced in structures of conventional design.

I claim:

45 A C-frame for a tractor comprising a hollow beam fabricated from steel plate sections welded together, said sections being of substantially the same thickness, the top section of said beam having an opening cut therein for reception of a steel plate insert therein, a steel plate insert disposed in said opening having an undersurface flush with the undersurface of the contiguous portions of said top section, a V-butt weld disposed in said top section around the perimeter of said insert and extending completely through said opening and joining said insert to the surrounding marginal portion of said section, said insert having a top surface substantially flush with the top of said adjacent V-butt weld and the adjacent upper surface of said top section, said top surface of said insert extending inwardly thereof a substantial distance from its marginal edge and having an upwardly extending portion providing a central portion of substantially greater thickness than its marginal edge and of constant thickness and the central portion and marginal edge being joined by a fillet portion, a vertical bracket member seated on said thickened central portion having an opening therein to receive a pivot pin for mounting a tractor blade thereon, the opposite bottom sides of said bracket adjacent the edges of said thickened central portion being provided with oppositely disposed recesses, and a weld disposed in each said recess joining said bracket and the marginal edge of said central portion together, said bracket welds

being formed to be substantially flush with said fillet portion and the contiguous bracket surface.
